UNITED STATES PATENT OFFICE.

HENRY D. JAMES, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROLLER.

1,354,193.

Specification of Letters Patent. Patented Sept. 28 1920.

Application filed May 16, 1916. Serial No. 97,849.

To all whom it may concern:

Be it known that I, HENRY D. JAMES, a citizen of the United States, and a resident of Wilkinsburg, in the county of Allegheny and State of Pennsylvania, have invented 5 a new and useful Improvement in Controllers, of which the following is a specification.

My invention relates to controllers for 10 electric motors and particularly to controllers that are employed in connection with motors requiring heavy currents in starting under load.

My invention has for one of its objects 15 to provide a mechanism of the above-indicated character in which the switching mechanism and the safety devices in connection therewith are embodied in a unitary mechanism.

20 A second object of my invention is to provide an improved mechanism for automatically retaining the operating handle of a controller in its operative position and for releasing the same upon the occurrence of 25 predetermined circuit conditions.

In the construction of controlling devices 30 of the same general character as that of my invention, it has been the usual practice to inclose the switching mechanisms in casings and to attach the usual overload devices and 35 no-voltage release mechanisms to the outer side of the casings. It will be readily appreciated that such an arrangement is not only unattractive in appearance but the mechanisms outside the casings are not protected in any way unless a separate casing is provided.

According to the present arrangement, I 40 so arrange the various parts of the controller that the switching mechanism and the no-voltage and overload devices may all be conveniently contained in a single casing. The various parts are not only protected by reason of their being inclosed, but the various coöperating parts may be located adjacent to each other.

My invention, which comprises numerous 45 other details, in addition to those set forth above, will be described in connection with 50 the accompanying drawings in which Figure 1 is a view, partially in elevation and partially in section, of a controller constructed in accordance with my invention. Fig. 2 is an enlarged view of the details of a portion 55 of the switching mechanism. Fig. 3

is a view, similar to Fig. 1, but taken at right angles thereto. Fig. 4 is a view of the details of a safety device.

Referring particularly to Figs. 1 and 2, the controlling mechanism comprises a casing 1 having a stationary part 2 that is adapted to be secured to any suitable support and a part 3 for inclosing the switching mechanism. The part 3, which may constitute a tank for oil, in case the apparatus 60 is employed in connection with high voltage circuits, is removably secured to the stationary part 2 by means of latching mechanisms 4. The casing further comprises a removable cover member 5 which is loosely 65 hinged to the member 3 by means of mutually engaging hook portions and is secured in position by a latching mechanism 6 that is located at the top of the casing.

The switching mechanism comprises two 70 rows of stationary contact members 7 that are mounted upon, and insulated from, supporting bars 8. A corresponding number of pairs of oppositely disposed movable contact members 9 are mounted upon and insulated 75 from a rocking shaft 10. The respective contact members 9 are pivotally supported by pins 11, and the members of each pair are yieldingly retained in their relative positions illustrated in Fig. 3 by means of coil 80 springs 12.

The several groups of coacting movable and stationary contact members are separated by arc shields or barriers 13 of insulating material that are supported by rods 14. 90 The rods 14 are suspended from the means for supporting the shaft 10 by a pair of spring clips 15 that are provided with suitable holes for receiving the ends of the rods. By means of this arrangement, the 95 arc shield structure may be readily removed when it is desired to inspect or repair the switch mechanism.

The switching mechanism is controlled by an operating handle 17 located outside the 100 casing and connected to a rotatable shaft 18 that is mounted in bearings 19. The shaft 18 is operatively connected to the shaft 10 by means of a segmental gear mechanism 20. The employment of segmental gear 105 wheels for connecting the operating shaft to the shaft for supporting the movable contact members permits the movable members of the switching mechanism to move through a circular path of much shorter 110

radius than would be possible if it were necessary to mount the movable switch elements directly upon the operating shaft 18.

The operating handle 17 is normally retained in its inoperative position by a centering device 21 which comprises a stationary pin 22, two oppositely disposed curved arms 23 that are pivotally supported by the shaft 18, a spring 24 which resists the separation of the arms 23, and a pin 25 that is mounted upon an arm 26. The arm 26 is secured to the shaft 18 and extends upwardly therefrom.

Means are provided, also, for insuring that the operating handle can be moved in one direction only from its inoperative position. A pivotally mounted latching member 27 is provided with a notch 28, one side 29 of which is inclined to the axis of the member 27 and projects laterally beyond the other side of the notch which is normal to the axis of the shaft. This arrangement insures that the handle 17 can be moved only in one direction from its inoperative position in which the pin 25 is seated in the notch 28. When the handle is operated to its starting position, the pin 25 is actuated to the right, as viewed in Fig. 3, to raise the member 27, whereupon the handle may be actuated in the opposite direction to its running position if it is moved rapidly.

The arm 26 is provided, at its upper end, with a projecting pin or rod 30 which coacts with a latching mechanism 31 to retain the arm 26 and its connected mechanism in their running positions. The latching mechanism 31 comprises a pivotally mounted arm 32 that is provided with a hook 33 extending at right angles thereto. The hook 33 is provided with a notch 34 and an inclined portion 35 for coacting with the pin 30. An electromagnet 36 retains the arm 32 in a vertical position when the pin 30 has been actuated into engagement with the notch 34. The switching mechanism and the handle 17 are retained in their respective running positions by the electromagnet 36 except upon failure of voltage, opening of the circuit of the electromagnet coil or other abnormal conditions to be later described.

A transformer 38, which is connected in circuit with the motor to reduce the voltage applied to the latter in starting, is secured to the casing member 2 by means of bolts 39 and spacing sleeves 40. An overload relay 41 is secured to the transformer 38 and is accordingly supported by the bolts 39. The relay 41 controls the circuit of the coil 42 of the electromagnet 36 and operates to open the circuit of the coil when the load exceeds a predetermined value.

A voltage transformer 42 for reducing the voltage applied to the no-voltage release magnet 36 is located immediately above the

transformer 38 and is secured to the casing member 2 by bolts 43. Suitable terminals 44 for connection to the line conductors are located in the upper portion of the casing and are supported by a rod 45. The terminals 44 are connected to a second set of terminals 46 located near the upper front portion of the casing in such position that they may be conveniently connected to the transformer 38 and to the switching mechanism and are accessible for the purpose of inspection or repair.

The terminal members 46 are mounted upon, and insulated from, a rod 47 which extends transversely of the casing. Disks 48 of insulating material are mounted on the shaft 47 near the sides of the casing and serve to prevent the cover member 5 from coming in contact with the terminal members 46 when the cover member is removed from the casing.

The casing member 5 is provided with a member 49 of insulating material which projects downwardly a sufficient distance to engage the arm 32 in case the latter is in its vertical position when the cover member 5 is moved from the casing. By means of this arrangement, it is impossible to remove the cover member 5 and allow the switching mechanism to remain in its running position.

Another arrangement for preventing the removal of the cover member 5 without first bringing the operating mechanism to its off position is illustrated in Fig. 4, in which similar reference numerals are employed to designate corresponding parts. The latching member 27 is provided with a projecting member 50 which coacts with a hook member 51 that is mounted on the cover member 5 to lock the latter in its closed position except when the pin 25 occupies the notch 28 in the member 27. The various parts occupy these relative positions only when the lever 17 and its connected mechanism are in their intermediate or inoperative positions.

Reference may now be had to Fig. 2, in which the details of a portion of the switching mechanism are illustrated. A member 52, to which a contact member 9 is secured, as shown in Fig. 3, is pivotally mounted on a pin 11. The stationary portion of the switch comprises a member 53 and a terminal member or conductor 54, all of which are retained in their respective illustrated positions by the pin 11. In assembling the switch mechanism, the members 52, 53 and 54 are placed in position relatively to the pin 11 before the ends of the latter are upset or riveted. By providing the pin 11 with reduced portions to form suitable shoulders, the sides of the stationary member 53 are spaced apart and are rigidly held in proper relation, and the terminal member 54 is se-

curely attached thereto. The advantage of this arrangement consists in the ease with which the various parts may be assembled and the small amount of labor required to 5 rivet the ends of the pin 11. All of the various parts except the pin 11 may be punched from metal plate of suitable thickness.

It may be assumed that the switching 10 mechanism is electrically connected in any suitable manner (not shown) to the primary windings of an alternating-current motor and that the various parts occupy their respective illustrated or inoperative 15 positions. To start the motor, the lever 17 is first actuated to rock the shaft 18 in a clockwise direction, as viewed in Fig. 3. The switching mechanism is thereby actuated to the right, as viewed in Fig. 3, to 20 effect the engagement of the contact members 7 and 9. The arm 26 and the pin 25 move to the right, and the latch member 27 is raised to its uppermost position.

When the motor has been accelerated sufficiently, the lever 17 is moved quickly in the opposite direction to its running position to effect a quick separation of the contacts 7 and 9 on the one side and to effect a correspondingly quick engagement of the 30 coacting contact members on the other side of the switching mechanism. A rapid movement of the mechanism is made necessary by reason of the fact that the latch member 27 engages the pin 25 and retains 35 the various parts in their respective inoperative positions unless the pin 25 is moved across the notch 28 before the latch member 27 is actuated by gravity to engage the pin.

40 When the arm 26 and the pin 30 are moved to the running position, the latter engages the arm 32 to actuate the latter to its vertical position in which it is retained by the electromagnet 36. The hook member 45 33 is in such position that it is not engaged by the pin 30 during the movement above described. As the arm 32 is moved to its vertical position, the hook member 33 rocks in a counter clockwise direction about its 50 point of pivotal support, and the pin 30 is thereby seated in the notch 34. The arm 26 and the various parts to which it is connected are retained in their respective running positions under all normal conditions. 55 The arm 32 is released, however, upon a failure of voltage and the resultant deenergization of the magnet 36 or upon the opening of the circuit of the latter by the over-load relay 41. The arm 32 will be with- 60 drawn from its vertical position to release the arm 26 in case the cover member 5 is removed from the casing while the various parts are in operative position by reason of the engagement of the arm 32 by the mem- 65 ber 49.

In case the arm 32 is released by the electromagnet 36, the arm 26 will be returned automatically to its intermediate position, and the arm 32 to its inoperative position by the centering device 21. When the arm 70 26 is actuated in either direction from its illustrated position, the pin 25 causes a movement of one of the arms 23 about its point of pivotal support. The spring 24, which is attached to the other arm 23, is 75 placed under tension, since the last mentioned arm is held in its normal position by the stationary pin 22. It is obvious, therefore, that movement of the arm 26 in either direction places the spring 24 under tension 80 and that the arm 26 is restored to its intermediate position when it is released by the latching mechanism 31 or when the handle 17 is released by the operator without first securing the switching mechanism in position by means of the latching mechanism 31. 85

I claim as my invention:

1. In a controller, the combination with a switching device, and a casing therefor comprising a cover member, of means comprising a latching mechanism for controlling said device, and a member connected to said cover member for actuating said controlling means upon the removal of said cover member under predetermined conditions. 90

2. In a controller, the combination with a switching device, and a casing therefor comprising a cover member, of latching means for controlling said device, and a member connected to said cover member for 100 actuating said latching means upon the removal of said cover member under predetermined conditions.

3. In a controller, the combination with a pair of relatively movable contact members, and a latching mechanism for controlling them, of a relatively movable inclosing member having means for actuating said mechanism upon the removal of said inclosing member when the contact members 105 are in operative position.

4. In a controller, the combination with a no-voltage release device, and means comprising a removable member for inclosing the same, of means actuated by said member for effecting the same operations as that of said device upon the removal of said member. 115

5. In a controller, the combination with a switch member, an electrical conductor, 120 and a member adapted to be secured to said conductor, of common means for pivotally supporting said switch member and for permanently connecting the other member to said switch member. 125

6. In a controller, the combination with a switch member, an electrical conductor and a terminal member adapted to be secured to said conductor, of a pin for pivotally supporting said switch member hav- 130

ing means comprising a shoulder portion and a riveted head portion for rigidly securing said terminal member thereto.

7. In a controller, the combination with 5 a pair of coacting contact members, of arc-shielding means for said contact members, a member for supporting said arc-shielding means and a pair of spring clips for engaging said supporting member.

10 8. In a controller, the combination with an electromagnet having an armature member connected thereto, of an element connected to said member having a projecting portion and a movable pin for engaging 15 said member to cause said projecting portion to lock the pin in one position.

9. In a controller, the combination with a switch member, and means tending to retain 20 said member in a central inoperative position, of means for retaining said member in an operative position, said retaining means comprising an electromagnet, a latching device controlled by said electromagnet and a member to be engaged by said device 25 when the latter has been actuated by said member into operative relation to said electromagnet.

10. In a controller, the combination with a pair of relatively movable contact members and means for controlling them, of a relatively movable inclosing member having means for actuating said controlling means, and latching mechanism for holding said controlling means in locked position.

35 11. In a motor controller, a casing, a transformer for the motor secured within said casing centrally thereof, a switching device at one end of said casing, means for controlling said device, a no-voltage release 40 device for controlling said controlling means within and at the other end of said casing, an overload device for controlling said no-voltage device carried by said transformer, and a voltage transformer for said 45 no-voltage device situated adjacent to said first-named transformer and said no-voltage device.

12. In a controller, the combination with a plurality of casings, and a cover member 50 for one of said casings hinged to another of said casings, of a switching device in one of said casings, and means connected to said cover member and in another of said casings for controlling said device.

55 13. In a controller, the combination with a plurality of casings, of a switching device in one of said casings, means for controlling said device in another of said casings, a cover member for said other casing, and a 60 member connected to said cover member for actuating said controlling means.

14. In a controller, the combination with a plurality of casings, of a switching device in one of said casings, means for controlling 65 said device in another of said casings, a

cover member for said other casing, and means connected to said controlling means and to said cover member for preventing the opening of said cover member when said controlling means is in an operative position.

70 15. In a controller, the combination with a switching device, and a casing therefor comprising a cover member, of means for controlling said device, latching safety 75 mechanism connected to said cover and to said means, and a member connected to said cover member for actuating said controlling means.

16. In a controller, the combination with 80 a casing having a stationary part and a cover member, and a stationary contact mechanism at one end of the stationary part, of a movable contact mechanism mounted on said stationary part adjacent 85 to said stationary contact mechanism, means for controlling said movable contact mechanism, and a member connected to said cover member and relatively removed from said contact members that is operable, when 90 the controlling means is in operative position, to actuate said controlling means upon the removal of said cover member.

17. In a controller, the combination with a switching device, and a casing therefor 95 comprising a cover member, of means for controlling said device, means for centering said controlling means, and means connected to both of said means for preventing the opening of said cover member when said 100 switching device occupies an operative position.

18. In a controller, the combination with a switching device, and a casing therefor comprising a cover member, of means for controlling said device, means for centering said device, and means rigidly connected to said cover member for initiating the actuation of said controlling means from an operative position to render the centering 105 110 means effective upon the removal of said cover member.

19. In a controller, the combination with a switching device and a containing casing 115 therefor having a cover member, of an arm for controlling said device, means for preventing the slow actuation of said arm in one direction and means connected to said preventing means for locking said cover member in its closed position.

120 20. In a controller, the combination with a stationary contact mechanism and a movable contact mechanism pivotally mounted adjacent thereto, of an arm for controlling said movable mechanism, a segmental gear 125 connection between said movable mechanism and said arm, means for actuating said arm, an electro-magnet having a movable armature, and a latching mechanism, said controlling arm being operable to ac- 130

20

tuate said armature and said latching mechanism to their respective operative positions.

21. In a controller, the combination with 5 a device and a latching mechanism for controlling it, of a relatively movable inclosing member adapted to actuate said mechanism upon the removal of said inclosing member when said device is engaged by said mechanism.

22. In a motor controller, a casing, a transformer for the motor secured within 10 said casing centrally thereof, a switching device at one end of said casing, means for controlling said device, a no-voltage release device for controlling said controlling means within and at the other end of said casing, and an overload device for controlling said

no-voltage device carried by said transformer.

23. In a motor controller, a casing, a transformer for the motor secured within 15 said casing centrally thereof, a switching device at one end of said casing, a pair of rods within and at the other end of said casing, terminal members mounted upon one 20 of said rods for connecting said switching device to a source of energy, and a second set of terminal members mounted upon the other of said rods for connecting said transformer to said switching device.

In testimony whereof, I have hereunto 25 subscribed my name this 26th day of April, 1916.

HENRY D. JAMES.
